AIR COOLER AND CONDITIONER

Richard C. Slater, Galesburg, Ill.

Application April 5, 1937, Serial No. 135,131

1. Claim. (Cl. 261—106)

This invention relates to a cooler and conditioner for air and it aims to provide a novel apparatus wherein an absorbent element is maintained saturated with water, air is drawn through the saturated element through the action of a fan, creating an unusual amount of evaporation, the latter causing the air to cool and also washing it as it is drawn through the mist and saturated means, thereby becoming conditioned.

It is also aimed to provide such a structure as may be used in connection with a room or enclosure, mounted in a window opening or in any other desired position.

The more specific objects and advantages will become apparent from a consideration of the description following taken in connection with accompanying drawing illustrating an operative embodiment.

In said drawing:

Figure 1 is a side elevation of the invention; 20 Figure 2 is a plan view of the invention;

Figure 3 is a vertical sectional view taken on the line 3—3 of Figure 2; and

Figure 4 is a detail horizontal sectional view taken on the line 4—4 of Figure 3.

Referring specifically to the drawing wherein like reference characters designate like or similar parts, 30 represents a casing of any desired shape to be used at any preferred location as in a window. Such casing 30 may be metallic, having an interior partition wall 31 equipped with a discharge opening therethrough surrounded by a continuous flange 23' within which a fan 25' is located, driven for instance by an electric motor 26' from any suitable source of current. 35 The interior wall of this casing has a discharge opening at 32, in communication with the room or space into which the conditioned air is to be discharged. A pan 33 extends rearwardly beyond the partition 31, at the base of the casing 30 and an absorbent web 14' of burlap, other cloth or the like, adapted to be saturated with water and maintained saturated, is angularly dis-

posed, being arcuate in horizontal section, and fastened in any suitable manner to the shelf 33 and to a rearward extension 34 of the top wall of the casing and supported by equidistantly spaced rods 34a extending from pan or extension 33 to extension 34 and supported by equidistantly spaced rods 34a extending from pan or extension 33 to extension 34. Water from any suitable source is supplied through a pipe 35, leading to an arcuate header 36, having discharge nozzles 37 connected thereto and arranged to discharge the water in a horizontal direction. The excess of water is caught by the pan 33 and it drains therefrom through a pipe 38. The supply of water through the pipe 35 is continuous and may be regulated or cut-off through operation of a valve 39 in said pipe.

As a result of the construction described, the water continuously discharges from the nozzles 37 onto the web 14', being regulated or cut-off 20 when desired by the valve 39. The apparatus is usually located in a window so that air passes from the exterior of the room through the moistened web 14', being cooled and washed and accordingly conditioned, and discharges through 25 opening 32 into the room.

I claim as my invention:

A device of the class described having a casing provided with a discharge opening, said casing having a rear wall provided with a discharge 30 opening, a semi-circular rearward extension on the casing adjacent the base thereof forming a pan, a rearward extension on the top wall of the casing, a web of porous material disposed angularly about the entire periphery of said ex- 35 tensions, spaced supporting means for the web extending between said extensions, means to supply water to the web adjacent the top thereof, a drain for the pan, and a fan operable to draw air through the web and discharge it through 40 said openings.

RICHARD C. SLATER.
